US0D1006644S

(12) **United States Design Patent** (10) Patent No.: **US D1,006,644 S**
(45) Date of Patent: ** Dec. 5, 2023

(54) **WATCH CASE**

(71) Applicant: **Cartier International AG**, Steinhausen (CH)

(72) Inventor: **Nicole Gimenez**, Mont-sur-Rolle (CH)

(**) Term: **15 Years**

(21) Appl. No.: **35/514,122**

(22) Filed: **Feb. 28, 2022**

(80) **Hague Agreement Data**

Int. Filing Date: **Feb. 28, 2022**

Int. Reg. No.: **DM/219396**

Int. Reg. Date: **Feb. 28, 2022**

Int. Reg. Pub. Date: **Apr. 29, 2022**

(51) **LOC (14) Cl. 10-02**

(52) **U.S. Cl.**

USPC **D10/38**

(58) **Field of Classification Search**
